UNITED STATES PATENT OFFICE.

AUGUST LIPSE AND JOSEPH MANGIARACINA, OF NEW ORLEANS, LOUISIANA.

STREET MARKER.

1,424,416.

Specification of Letters Patent. Patented Aug. 1, 1922.

Application filed July 27, 1921. Serial No. 487,949.

To all whom it may concern:

Be it known that we, AUGUST LIPSE and JOSEPH MANGIARACINA, citizens of the United States, residing at New Orleans, in the 5 parish of Orleans and State of Louisiana, have invented certain new and useful Improvements in Street Markers, of which the following is a specification.

This invention has as its object to provide 10 a machine for use in applying strips of paint to street surfaces to indicate parking spaces, crossings, safety zones, etc. Heretofore this task has been performed by more or less laborious and time wasting methods, and the 15 present invention therefore contemplates the provision of a machine which in its operation will merely require to be propelled in front of the operator and in the proper direction or course and which will, as it is 20 propelled, apply a strip of paint to the street surface.

Another object of the invention is to provide a machine for the purpose stated so constructed that it will not be wasteful of 25 the paint and will insure the flow of paint to the applying brush or other medium and will at all times be under the control of the operator of the machine.

The machine of the present invention includes 30 a reservoir for the paint, a brush or the like for applying the paint to the street surface, and means for delivering the paint from the reservoir to the brush, and another object of the invention is to provide means 35 under the control of the operator and operable to lower the brush or other applying medium into contact with the street surface and simultaneously open a valve controlling the supply of paint from the reservoir to 40 the brush, means being provided in connection with the last mentioned means for normally acting upon the same to hold the applying medium elevated clear of the street surface and in the meantime the valve closed 45 so that while the machine is being propelled from place to place and not in actual operation, no paint will be supplied to the brush.

Other novel features of the invention reside 50 in the construction and arrangement of the various component parts of the machine.

In the accompanying drawings:

Figure 1 is a side elevation of the machine embodying the present invention, certain of the parts being shown in full lines in normal 55 or inactive position and in dotted lines in active position.

Figure 2 is a bottom plan view of the machine.

Figure 3 is a group prospective view illustrating the paint applying brush and its 60 associated parts.

Figure 4 is a detail view partly in elevation and partly in section illustrating the valve for controlling the supply of paint from the reservoir to the brush and the 65 means provided for actuating this valve.

The machine embodying the present invention comprises a tank or reservoir for containing the paint, which reservoir is indicated in general by the numeral 1 and is 70 supported for travel preferably in the manner illustrated in the drawings wherein the numeral 2 indicates an axle supporting ground wheels 3 at its ends, and the numeral 4 indicates a tongue which is secured at its 75 forward end to the intermediate portion of the axle and is provided, rearwardly of the axle, with one or more cross pieces 5 as best shown in Figures 1 and 2 of the drawings. The reservoir 1 is supported upon the upper 80

side of the axle 2 and tongue 4 and upon the cross pieces 5, and may be secured to these supporting parts in any manner found suitable. The reservoir is so positioned that the axle 2 will be located a short distance rearwardly of the forward end of the reservoir, and the tongue 4 at its rear portion extends beyond the rear end of the reservoir and is provided with handles 6 which may be grasped for the purpose of propelling the 90 machine over the street surface. In order that the operator of the machine may be relieved of the weight of the reservoir 1 and the supporting structure comprising the tongue 4 and cross pieces 5, a third wheel or 95 runner 7 is preferably provided and is mounted in a suitable bearing yoke 8 at the lower end of a bracket 9 which is secured to the underside of the tongue 4, the wheel 7 being located in rear of the wheels 3 and 100 being designed, as stated, to sustain the weight of the rear portion of the machine, the forward portion of the machine being supported by the axle 2 and wheel 3.

Paint is to be delivered from the reservoir 105 1 through a supply pipe 10 which leads laterally and downwardly from one side of the reservoir 1 at the lower and forward end thereof, this pipe being arranged to discharge the paint flowing through, in such 110 a manner that the paint will be delivered to the brush by which it is to be applied to

the street surface, as will presently be explained. Interposed in the pipe 10 at a suitable point, is a valve 11 which may be any ordinary type of cut-off valve having the usual squared stem 12. A bracket 13 is secured to the axle 2, and mounted for oscillatory movement in this bracket is a shaft indicated by the numeral 14. The shaft 14 is in alignment with the stem 12 of the valve 11, and its end which is next adjacent the valve is provided with a squared socket 15 receiving the squared end of the valve stem 12 as clearly shown in Figure 4 so that in this manner operative connection is provided between the said shaft 14 and the stem of the valve, and therefore when the shaft is rotated in one direction the valve will be opened and when the shaft is rotated in the opposite direction the valve will be closed.

In order that the shaft 14 may be rotated for the purpose of controlling the valve 11 and for another purpose to be presently explained, a crank arm 16 is fixed upon the shaft at a point nearly in alignment with the tongue 4, and a rod 17 is pivotally connected at its forward end as at 18 through the end of the arm 16 and is extended slidably through suitable guides 19 longitudinally beneath the reservoir 1 and beside the tongue 4. A spring 20 is connected at one end as at 21 to the rod 17 at a suitable point in its length and at its other end as at 22 to some fixed portion of the structure in advance of the connection 21, as for example to the axle 2 as clearly shown in Figure 2 of the drawings. The spring 20 normally urges the rod 17 in a forward direction and when the rod is so moved, the shaft 14 is so rotated as to close the valve 11 and cut off the supply of paint through the pipe 10. In order that the rod 17 may be shifted in a rearward direction against the tension of the spring 20 and so as to rock the shaft 14 to open the valve 11, the rear end of the rod is turned laterally at right angles as indicated by the numeral 23 and has fitted to it a hand grip 24 extending in parallel relation to the handle 6 at the corresponding side of the tongue 4 and a short distance in advance of said handle. When it is desired to open the valve 11 and supply paint to the brush or other applying medium, the operator of the machine will grasp the handle 24, pulling the same rearwardly to position against the handle 6 which latter handle will likewise be grasped by the same hand, and the parts will be maintained in this position so long as it is desired to supply paint to the brush. When it is desired to cut off the supply of paint, it will be only necessary for the operator to release the handle 24 whereupon the spring 20 will automatically return the rod 17 to its normal position, and the shaft 14 will be rotated to

close the valve 11. It will be observed by reference to Figure 2 of the drawings that when the rod 17 is shifted to the limit of its forward movement, the angularly bent rear end 23 will abut against the rearmost one 70 of the guides 19, and thus the movement of the rod in the direction stated will be limited.

From the pipe 10, the paint is delivered into a trough indicated in general by the numeral 25 and comprising a fixed upper section indicated by the numeral 26 and an oscillatory lower section 27, the latter section 27 supporting the brush above mentioned. The fixed section 26 of the trough comprises 80 a bottom 28 and upstanding side walls 29, and this section is supported in fixed relation to the axle 2 by means of bracket arms 30 secured to the axle and to the outer side of the side walls 29, the section occupying 85 nearly a vertical position as shown in Figure 1. The oscillatory section 27 of the trough comprises a bottom 31 and upstanding side walls 32, and this section is of sufficiently greater width than the section 26, to 90 receive the lower end of the said section 26 within its rear or upper portion as clearly shown in Figure 3, pivots 33 being secured through the upper ends of the walls 32 and lower ends of the corresponding walls 29 and 95 serving to pivotally support the section 27 at the lower end of the fixed section 26 so that it may have swinging movement in an up and down direction. In order that a fluid-tight connection may be provided between 100 the connected ends of the sections 26 and 27, the bottom wall 28 of the section 26, at its lower end, is preferably curved forwardly on an arc having the axes of the pivots 33 as a center as indicated by the numeral 34, 105 the under side of the forward edge of the portion 34 being in close contact with the upper side of the bottom 31 of the section 27 in all positions of adjustment of the said section 27 about its pivotal connection with the section 26. The pipe 10 at its lower portion below the valve 11, is directed downwardly and forwardly within the trough comprising the sections 26 and 27 and may terminate at any point found desirable, so 110 that when the valve 11 is open, paint will flow from the reservoir 1 through the pipe 10 and into the trough 25.

The brush is indicated in general by the numeral 35 and the same comprises a head 36 and the usual bristles 37. The brush may be of any desired construction and of any suitable dimensions but preferably its head 36 is of a width to fit more or less snugly transversely within the lower end 115 of the trough section 27. The brush 35 is held in place within the trough section 27 by means of a clamping screw 38 which is adjustably threaded through the intermediate portion of a cross bar 39 which extends 120

transverse of the open upper side of the said trough section, the lower end of this clamping screw bearing against the upper side of the brush head 36 and binding the 5 lower side of the head against the bottom of the said trough section. However in order that the brush may be suitably spaced throughout the greater portion of the area of its under side, from the upper side of 10 the bottom 31 of the trough section and thus permit the paint which is discharged into the said trough section, to flow beneath the head of the brush and to the bristles 37 thereof, ribs 40 are provided up- 15 on the upper side of the said bottom 31 beneath and in advance of the cross bar 39, and these ribs may constitute strips suitably secured upon the upper side of the said bottom 31, or the ribs may be stamped up 20 directly from the bottom or otherwise formed integrally therewith. The ribs 40 preferably extend along relatively diverging lines in the direction of the forward or lower end of the trough section 27 so 25 as to suitably retard the flow of paint to the brush and more effectually distribute the paint and particularly insure of a plentiful supply at the opposite sides of the bristle body of the brush so that as the 30 brush is drawn over the street surface, a well defined stripe of uniform width will be painted upon said surface.

In order that when the shaft 14 is rocked so as to open the valve 11, the section 27 of 35 the trough may be simultaneously lowered to bring the brush 35 into contact with the street surface over which the machine is being propelled, an arm 41 is secured to one of the walls 32 of the section 27 at 40 the rear end thereof and in rear of the respective pivot 33, and extends upwardly and rearwardly beyond the said section 27 and is formed with a longitudinally extending slot 42. A crank arm 43 is secured upon the shaft 14 and is provided at its lower end with a pin 44 which works in the slot 42. Normally the spring 20 will hold the rod 17 shifted forwardly to the limit of its movement in this direction and at such time the shaft 14 will be rotated to such position that the valve 11 will be closed and the trough section 27 and the brush 35 carried thereby will be supported in the elevated position shown 50 in full lines in Figure 1 of the drawings. When it is desired to bring the machine into operation, the handle 24 is grasped and pulled rearwardly to the adjacent handle 6, thus rearwardly shifting the rod 17 and 55 rocking the shaft 14 so as to open the valve 11 and swing the arms 43 and 41 rearwardly thus lowering the section 27 of the trough and the brush 35 carried thereby, to the dotted line position shown in Figure 1 in

which position of the parts the bristles of 65 the brush will be in contact with the street surface, and as paint is now being supplied to the trough through the pipe 10 and the open valve 11, the paint will be applied by the brush to the said surface. 70

Having thus described the invention what is claimed as new is:

1. In a machine of the class described, a reservoir supported for travel, a liquid applying medium supported for movement into and out of operative relation to the surface over which the machine is propelled, and means for conducting liquid from the reservoir to the said medium. 75

2. In a machine of the class described, a reservoir supported for travel, a liquid applying medium supported for movement into and out of operative relation to the surface over which the machine is propelled, and means automatically operable to supply liquid from the reservoir to the medium when the latter is in operative relation to the surface and to discontinue such supply when the medium is out of operative relation to the surface. 80 85

3. In a machine of the class described, a reservoir supported for travel, a liquid applying medium supported for movement into and out of operative relation to the surface over which the machine is propelled, means for conducting liquid from the reservoir to the said medium including a controlling valve, and means operable to adjust the medium and simultaneously actuate the valve. 90 95

4. In a machine of the class described, a reservoir supported for travel, a liquid applying medium supported for movement into and out of operative relation to the surface over which the machine is propelled, means for conducting liquid from the reservoir to the medium including a controlling valve, an actuating member, manually operable means for operating the same, and operative connection between the actuating member 100 and the said medium and between the actuating member and the valve for effecting simultaneous adjustment of the medium and valve upon operation of the said member. 105 110

5. In a machine of the class described, a reservoir supported for travel, a liquid applying medium supported for movement into and out of operative relation to the surface over which the machine is propelled, means for conducting liquid from the reservoir to the said medium including a controlling valve, a rock shaft, manually operable means for rocking the shaft, operative connection between shaft and the said medium for effecting movement of the latter when the same is rocked, and operative connection between the shaft and the valve for adjusting 115 120 125

the latter when the shaft is rocked and in consonance with the adjustment of the applying medium.

6. In a machine of the class described, a reservoir supported for travel, a liquid applying medium supported for movement into and out of operative relation to the surface over which the machine is propelled, means for conducting liquid from the reservoir to the said medium including a controlling valve, a rock shaft, a tongue extending rearwardly from the reservoir, a rod slidably supported upon the tongue and operatively connected with the rock shaft to provide for movement of the latter when the rod is shifted, means whereby the said rod may be manually operated, a spring yieldably holding the rod shifted in one direction, operative connection between the rock shaft and the applying medium, and operative connection between the said shaft and the valve.

7. In a machine of the class described, a reservoir supported for travel, a liquid applying medium comprising a trough having a section supported for up and down swinging movement, means for conducting liquid from the reservoir to the trough, and a brush supported within the trough in position to be supplied with liquid discharged into the trough.

8. In a machine of the class described, a reservoir supported for travel, a liquid applying medium comprising a trough having a section supported for up and down swinging movement, means for conducting liquid

from the reservoir to the trough, the means for supplying liquid from the reservoir to the trough including a controlling valve, and manually operable means for simultaneously effecting adjustment of the trough section and the said valve. 40

9. In a machine of the class described, a reservoir supported for travel, a trough including a fixed section and a swingingly adjustable section movable in an up and down direction, means for supplying liquid from the reservoir to the trough, the said movable section of the trough being provided upon the upper side of its bottom with spacing means, and a brush disposed and held within the trough and supported by the spacing means in spaced relation to the bottom of the trough. 45 50

10. In a machine of the class described, a reservoir supported for travel, a trough including a movable section supported for up and down swinging adjustment, means for adjusting the said trough section, means for conducting liquid from the reservoir to the said trough section, spacing ribs upon the upper side of the bottom of the section diverging in a forward direction, and a brush held within the trough with its head resting upon the said ribs and spaced thereby from the bottom of the trough. 55 60 65

In testimony whereof we affix our signatures.

AUGUST LIPSE. [L. S.]
JOSEPH MANGIARACINA. [L. S.]
